GAME APPARATUS

Claude R. Kirk, Oak Park, and Edward E. Collier, Chicago, Ill., assignors to Standard Ticket Games Corporation, Chicago, Ill., a corporation of Illinois

Application June 28, 1934, Serial No. 732,776

12 Claims. (Cl. 273—121)

This invention relates to a game apparatus.

It is an object of this invention to provide an improved game apparatus which is relatively simple and inexpensive in construction and efficient in use.

Another object of this invention is to provide, in a game apparatus, the combination of: a cabinet having a dispensing outlet and including a member providing an inclined playing surface having ball exit or scoring openings formed therein; means for propelling balls one at a time onto the upper portion of said playing surface so that they may gravitate thereover and enter into a pass through said ball exit or scoring openings; means for elevating the balls one at a time from a point below said scoring openings to said propelling means; runways below and in communication with said scoring openings for returning the played balls from the latter to said 10 elevating means; a score recording or printing device arranged in said cabinet and including a rotatable print drum; means including devices actuated by balls traveling along said runways for rotatably advancing said printing drum in a 15 step by step movement in accordance with the scoring value of the played balls; an impression-receiving member in said cabinet and having the form of a tape or web of paper or the like; means including a pressure member coacting with said 20 elevating means and with said printing drum for printing the total score of the game upon a portion of said tape or web, after a predetermined number of balls have been elevated to said propelling means; and means for severing the 25 said score-bearing printed or ticket portion of the said web from the body of the latter after the score-printing operation and for dispensing the said score-bearing printed portion of said web exteriorly of the cabinet to the player through 30 40 said dispensing outlet.

An additional object of the invention is to provide a coin-controlled amusement game of the so-called marble or pin game type comprising: a cabinet; and means in the cabinet for printing 45 the total score of a game after a predetermined number of balls have played and for dispensing exteriorly of said cabinet to the player a printed score-bearing ticket or the like.

Other objects will appear hereinafter.

50 The invention consists in the novel combination and arrangement of parts to be hereinafter described and claimed.

The invention will be best understood by reference to the accompanying drawings, showing the 55 preferred form of construction and in which:

Fig. 1 is a top plan view of a game apparatus embodying a preferred form of the invention;

Fig. 2 is an end elevational view of the cabinet shown in Fig. 1;

Fig. 3 is a vertical longitudinal sectional view 60 on line 3—3 in Fig. 1, showing certain parts of the operating mechanisms of the new apparatus;

Fig. 4 is a top plan view on line 4—4 in Fig. 3;

Fig. 5 is a bottom plan view of the mechanisms shown in Fig. 4; 65

Fig. 6 is a sectional view on line 6—6 in Fig. 4;

Fig. 16 is a sectional view on line 16—16 in Fig. 4;

Fig. 17 is a sectional view on line 17—17 in 85 Fig. 6;

Fig. 18 is an enlarged fragmentary elevational detail view of part of the mechanism shown in Figs. 11 and 12; and

Fig. 19 is a sectional view on line 19—19 in 90 Fig. 18.

The new game apparatus comprises, in general, a cabinet, generally indicated at 20, and within which is arranged an inclined playing board 21. The inclined playing board 21 is provided with ball exit or scoring openings 22. Arranged at one side of the inclined playing board 21 is a ramp or runway 23 (Fig. 1) and arranged at the lower end of the ramp or runway 23 is a propelling device or plunger 24 by means of which 95 balls may be propelled, one at a time, along the ramp 23, onto the upper portion of the inclined playing board 21 so that they may gravitate over the latter and enter into and pass through the ball exit or scoring openings 22; the balls being elevated to the playing surface, onto the ramp 23 and in front of the propelling device 24, by means of an elevating device, generally indicated at 32 and including a manually operated lever or handle 33. 100 105 110

Arranged below the inclined playing board 21, and each having communication with a pre-selected group of the ball exit or scoring openings 22, is a group or series of inclined ball runways 25 (Fig. 4) by which the played balls are returned from the scoring openings. At the lower end of each ball runway 25 (Figs. 10 and 12), and in communication therewith, is a vertical ball chute 26, and projecting into each of these ball chutes 26 is an enlarged end portion 27 of a timing gear lever or arm 28. Adapted to be operated at different times by each of the arms is a score recording or printing device, generally indicated at 29 (Fig. 4) which includes a rotatable printing drum 34; and associated with the score recording or printing drum 34 is an impression-receiving tape or web 30 (Figs. 3, 4, and 16) upon which the player's total score is printed at the end of each game; the printed score-bearing portion of the web 30, or ticket, being severed from the web and dispensed exteriorly of the cabinet 20, to the player, through a dispensing outlet 31 which is formed in the lower end wall 125 of the cabinet 20 (Fig. 2).

Having thus generally outlined the structure of the new game apparatus, a general description of the operation of the same will be given before proceeding with the detailed description of its structure and operation so that the latter may be better and more intelligently understood.

The playing balls 167 are elevated, one at a time, onto the ramp 23, in front of the propelling device or plunger 24, by operation of the elevating device 32, which is accomplished by depression of the hand lever 33 (Fig. 3); the balls being propelled one at a time along the ramp 23 onto the upper portion of the inclined playing board 21 so that they may gravitate over the latter and pass through the ball exit or scoring openings 22. Upon passing through one of the ball exit or scoring openings 22 the played ball drops into the corresponding one of the runways 25 and, rolling down the latter, drops into the corresponding vertical chute 2 wherein it falls upon the enlarged end portion 27 of the corresponding timing gear lever 28, thereby depressing the latter (counterclockwise, Fig. 12). This movement of the thus ball-actuated timing gear lever 27-28 is imparted to a corresponding one of a series of counter-weighted timing gear carriages 57, each having a counter-weight 175, (Figs. 11 and 12) and each of which includes a main timing gear 56 and an auxiliary timing gear 59; the motion of the thus actuated timing gear carriage 57 releasing a latch bar 61 from latching engagement with the main timing gears 56, (Figs. 11 and 12); whereupon a tensioned main operating spring 168 (Figs. 6 and 17) rotates the shaft 55 and the printing drum 34 which are mounted on the shaft 55; and after the game is completed a pressure member or impression-transferring member 87 (Fig. 13) is actuated to move the web 30 into printing engagement with the printing drum 34, thus recording upon the tape or web 30 the player's total score for the game. During this operation the score-bearing portion of the web or tape 30 is severed from the body of the web by a knife 135 (Fig. 14) and is dispensed exteriorly of the cabinet 20, to the player, through the dispensing outlet 31 (Fig. 2).

Having thus generally outlined both the structure and operation of the new game apparatus a detailed description of the structure will now be given, following which a detailed description of the operation of the new game apparatus will be given.

From the ball runways 25 and vertical chutes

26 the played balls pass into a common runway or magazine 35 (Figs. 4, 6, 7, 9, 10, 11, and 12) by which they are directed to the ball-elevating device, generally indicated at 32. This ball elevating device 32 comprises a rotary elevator member or disc 36 in which is formed a series of ball-receiving pockets 37. This rotary elevating disc 36 is arranged within a housing or casing 38, which is in turn arranged in the cabinet 20, and the transverse runway or magazine 35 communicates at its lower end with the casing 38 by way of an inlet 39 (Fig. 6) so that the balls may be fed one at a time, by gravity from the magazine 35 into the pockets 37 of the rotary elevator disc 36.

The pockets 37 of the rotary elevator disc 36 are axially inclined (Fig. 6) toward the ramp 23 so that when the balls are elevated one at a time up to the level of the ramp 23 they will roll by gravity out of the pockets 37 in the rotary elevator disc 36 into the ramp 23 in front of the propelling device 24; the balls passing from the elevator pockets 37 into the ramp 23 by way of an opening 40 (Fig. 3) which is formed in one side wall of the elevator housing 38.

The rotary elevator disc 36 is mounted upon a horizontal elevator shaft 41 (Fig. 6); one end portion of the shaft 41 being journaled in a wall of the elevator housing 38 and the other end portion of the shaft 41 being journaled in a vertical supporting wall 42 which is provided in the cabinet 20. Formed upon the axially outer side of the elevator disc 36 is a ratchet 43 (Figs. 3 and 6) with which is associated an operating pawl 44 (Fig. 3). One end portion of the pawl 44 is pivotally connected, as at 45, to a link 46, and the latter is in turn attached to the elevator operating handle or lever 33 (Fig. 3); the elevator operating handle or lever 33 being pivotally mounted upon one wall of the elevator housing 38, as at 47. The pawl 44 has an angled end portion 48 (Fig. 4) which projects through an opening 49 formed in a wall of the elevator housing 38 (Fig. 3) into engagement with the teeth of the ratchet 43 so that the rotary elevator disc 36 can be rotated (counterclockwise, Fig. 3) by depressing the hand lever 33, thereby pivoting the link 46 and pawl 44 from full to dotted line position, (Fig. 3), so as to elevate the balls 167 one at a time up onto the ramp 23, in front of the propelling device or plunger 24, as will readily be understood by an examination of Fig. 3.

Pivotedly mounted between its ends upon a wall of the elevator housing 38, as at 50, is a dog 51. This dog 51 has an end portion 52 which is urged by a spring 53 (counterclockwise, Fig. 3) into engagement with the teeth of the ratchet 43 so as to prevent retroactive movement of the rotary elevator disc 36.

Having one end rotatably journaled in the vertical supporting wall 54, (Fig. 6), and arranged in the cabinet 20 below the inclined playing board 21, is the horizontal shaft 55, (Figs. 4, 6, and 9). Fixed upon this shaft 55 for rotation therewith and spaced at intervals axially therealong are the main timing gears 56 (Figs. 4, 6, 11 and 12). The timing gear levers 27-28 are formed as parts of the counterweighted timing gear carriages 57 (Figs. 11 and 12) and these carriages 57 are pivotally mounted upon, that is, loosely float upon a common horizontal shaft 58 which extends parallel to the shaft 55 (Figs. 6, 11 and 12). Each of the timing gear carriages 57 includes a counter-weight 175. Pivotedly mounted upon each one of these carriages 57 is an auxiliary timing gear 59, and one of these auxiliary timing gears 59 is en-

150

gaged with a corresponding one of the main timing gears 56 when a played ball drops from a runway 25 into the corresponding vertical chute 26 and onto the corresponding timing gear lever 5 27-28 (Figs. 11 and 12). When a ball passes through one of the exit or scoring openings 22 in the inclined playing board 21, into the corresponding one of the runways 25, it passes from the runway 25 into the corresponding vertical chute 26 and drops down the latter onto the enlarged portion 27 of the corresponding timing gear carriage arm 28; thereby pivoting the corresponding timing gear carriage 57 (clockwise, Fig. 11, counterclockwise, Fig. 12), 10 upon its supporting shaft 58. This movement of the actuated timing gear carriage 57 meshes the auxiliary timing gear 59 carried thereby with the corresponding main timing gear 56 and at the same time pivots a latch bar 61, which is carried by and common to all of the timing gear carriages 57, out of engagement with the main timing gears 56 (Figs. 11 and 12). This frees the shaft 55 and the main timing gears 56 and the printing drum 34 carried thereby for rotation under the action 15 of the main operating spring 168 wherupon the shaft 55 and the timing gears 56 and printing drum 34 carried thereby are rotated; the engagement of the actuated auxiliary timing gear 59 with its main timing gear 56 timing the duration 20 of rotation of the shaft 55 (counterclockwise, Fig. 11, clockwise, Fig. 12), and the printing drum 34 carried thereby, as will be explained more fully hereinafter.

To this end there are pivotally mounted below 25 the playing board 21, upon a horizontal shaft 62 (Figs. 11, 18 and 19) a series of spaced timing levers 63. Each of these timing levers 63 has an end portion 64 which projects through a slot 65 which is formed in a lateral extension of the corresponding timing gear carriage 57 (Fig. 19). Formed on the end portion 64 of each timing lever 63 is a lateral extension which provides a cam 66 and projecting laterally from each of the timing gears 59 is a pin 67, (Figs. 11, 12, 18 30 and 19). When one of the timing gear carriages 57 is actuated by a played ball to engage the corresponding auxiliary timing gear 59 and main timing gear 56, the pin 67 carried by the auxiliary timing gear 59 rides up the corresponding cam 66. However, as the shaft 55 and the gears 56 are rotated (counterclockwise, Fig. 11, clockwise, Fig. 12) by the tensioned main operating spring 168, the actuated timing gear 59 tends to rotate in an opposite direction (clockwise, Figs. 11 and 18, counterclockwise, Fig. 12), thus causing the pin 67 carried thereby to ride off the cam 66 and thus pivot the actuated carriage 57 at 58 in a direction to disengage the auxiliary timing gear 59 from the corresponding main timing gear 56. 35 At this time the latch member 61, which is carried by and common to all of the timing gear carriages 57, is urged by its resetting spring 173 back into engagement with the main timing gears 56 and thereby stops the rotation of the shaft 55, gears 56, and printing drum 34. In this manner the printing drum 34 is rotated or advanced in a step by step movement in accordance with the scores made by the balls played through the scoring openings 22 in the inclined playing board 21 into the runways 25, and after the player has elevated a predetermined number of balls to the propelling device 24, and has completed a game, the impression-transmitting or pressure member 87 forces the impression-receiving web or tape 30 against the printing type 60 which are pro-

vided on the peripheral surface of the printing drum 34, and thereby prints the player's total score upon the web 30; and during this printing operation that portion of the tape or web 30 having the total score of the game thus printed thereon is forced by the pressure member 87 against the knife 135 and is thereby severed from the web 30 and dispensed to the player through the dispensing outlet 31.

The transverse ball return runway 35 comprises a terrace of steps (Figs. 11 and 12) and as the balls pass down this runway 35 they successively fall upon and engage an arm 69 of a dog 70 (Figs. 10 and 11), thereby moving the arm 75 of the dog 70 out of engagement with the teeth of a ratchet 71, whereupon a tensioned spring 73, which is arranged upon the shaft 72, rotates the ratchet 71 and its supporting shaft 72 in a step by step rotary movement (clockwise, Figs. 10 and 11), the member 70 including an escape-pawl or check arm 76. After a predetermined number of balls have been elevated to the propelling means 24 the ratchet 71 will have been stepped around until its arm 75 comes into contact with an uninterrupted cam surface 100 74 that is provided on the periphery of the ratchet 71, whereupon the tensioned spring 73 rotates the ratchet 71 and its supporting shaft 72 (clockwise, Figs. 10 and 11). This rotation of the shaft 72 causes an arm 105 77 which is fixed thereon (Fig. 15) to engage one arm 78 of a latch member 79, which is pivotally mounted between its ends, as at 80, (Fig. 15), upon a vertical supporting wall 92, thereby pivoting the other end portion 81 of the latch member 79 out of latching engagement with a notched portion 82 of a cam 83 that is mounted on a horizontal shaft 84. A tensioned spring 68 on the shaft 84, (Figs. 5 and 15) which carries the cam 83, then rotates the shaft 110 84 and cam 83 (clockwise, Fig. 15). This motion of the cam 83 moves an arm 85, which is eccentrically connected to the cam 83, as at 86 (Fig. 15) in a direction to move the impression-transmitting or pressure member 87 (Fig. 13) 115 against the tape or web 30 and thereby force the latter against the printing drum 34; one end of the eccentric arm 85 being pivotally connected to the pressure member 87 by means of a pin 88 (Figs. 4 and 15).

The pressure member 87 includes a pair of spaced arms 89 which are swingingly mounted at their upper ends upon a shaft 90 (Figs. 13 and 14); the pin 88 extending between the lower end portions of the arms 89 and one end portion of the pin 88 projecting through and being guided in a slot 91 which is formed in the vertical supporting wall 92 which is arranged within the cabinet 20 (Fig. 14).

The stationary web-cutting knife or cutting element 135 is mounted upon the vertical supporting wall 92 (Figs. 4 and 14) and the ticket or score-bearing portion of the tape or web 30 is severed from the body of the same by the shearing engagement between one of the arms 139 of the pressure member 87 and the cutting edge 93 of the knife 135; to this end the pressure member 87 being shifted laterally (right to left, Fig. 14) by a spring 177 which is arranged upon the shaft 90 between the supporting wall 143 and the pressure member 87 (Figs. 4 and 13); this severing operation taking place as the web 30 is forced against the printing drum 34 by a flat spring 123, which is mounted on the pressure member 87, to print the player's total score 150

thereon, (Figs. 4, 5 and 13). In this manner the score-bearing portion of the web 30 or ticket is severed substantially simultaneously with the printing operation and falls upon a gravity chute 94 (Fig. 14) by which it is dispensed to the player, exteriorly of the cabinet 20, through the dispensing slot 31 (Fig. 14); it being noted that the web 30 is fed through a slot 95 (Fig. 14), which is formed in the vertical supporting wall 92, past the cutting edge 93 of the knife 135 and across the face of the printing drum 34.

The web 30 is guided between vertical guide rollers 96 and 97 (Figs. 4 and 16) and is fed through the slot 95, across the cutting edge 93 of the knife 135 and across the peripheral printing surface of the printing drum 34, by means of a web advancing roll 98 which is provided with projecting lugs 99; the lugs 99 engaging through corresponding perforations in the web 30 (Figs. 4, 6, and 16).

Extending transversely across the cabinet 20 and suitably supported therein (Fig. 4) is a horizontal shaft 100 which carries at one end a beveled gear 101 (Figs. 5 and 6). This beveled gear 101 meshes with a corresponding beveled gear 102 and the gear 102 is mounted upon a vertical shaft 103 at the lower end of the latter (Fig. 6); this shaft 103 carrying the web-advancing roll 98. At its other end the shaft 101 carries a sprocket 104 with which is associated a sprocket chain 105 (Fig. 9).

Mounted on the elevator shaft 41 (Fig. 6) is a sprocket 106 around which the sprocket chain 105 revolves, the sprocket chain 105 also working around a sprocket 108 which is mounted upon the shaft 84, the shaft 84 having one end rotatably journaled in the vertical supporting wall 92 and having its other end rotatably journaled in a bracket 109 which is attached to the supporting wall 42 (Figs. 5, 6, and 9).

Motion is imparted to the web-advancing roller 98 by operation of the elevator operating hand lever 33, which in turn operates the rotary elevator disc 36, this operation being as follows: when the elevator operating lever 33 is depressed (Fig. 3) it rotates the elevator disc 36 and the elevator shaft 41 (counterclockwise, Fig. 3, clockwise, Fig. 9) thereby rotating the sprocket 106, sprocket chain 105, sprocket 104, and shaft 100 (clockwise, Fig. 9). This rotation of the shaft 100 is imparted through the beveled gears 101 and 102 to the vertical shaft 103 upon which the web-advancing roll 98 is mounted, thereby rotating the latter and advancing the web 30 therefrom through the slot 95 in the wall 92 across the cutting edge 93 of the knife 135 and across the peripheral surface of the printing drum 34; a pair of intermeshing gears 107 and 110 being provided on the shafts 55 and 41 respectively (Figs. 6 and 9), for reasons to be made apparent hereinafter.

Mounted on the shaft 100 (Figs. 5 and 15) is a disc 111 upon which are arranged a radially arranged row of laterally extending pins 112 which are successively engageable with an end portion 113 of an arm 114; the arm 114 being formed as a depending extension of a stop member 115 (Fig. 15) which is pivotally mounted upon the supporting wall 92, as at 116. This stop member 115 includes an abutment arm 117 which is arranged in the path of movement of a lateral extension 118 of the disc 83.

As the web-advancing roller operating shaft 100 is rotated (clockwise, Fig. 15) the radially arranged pins 112 successively engage the

foot portion 113 of the stop member 114—115 of its resetting spring 174 (clockwise, Fig. 15) and thus lifting the abutment or stop arm portion 117 of the stop member 115 out of the path of movement of the lateral extension 118 of the disc 83, thereby freeing the disc 83 and shaft 84 for rotation by the spring 68 and thus also freeing the pressure member 87 so that the same may be operated when, at the end of the game, the latch member 78—79—81 is moved out of latching engagement with the notched portion 82 of the disc 83 by action of the arm 77 on the ratchet supporting shaft 72 (Fig. 15).

The new game apparatus is intended to be coin-controlled and to this end a suitable coin-controlled device, which includes a coin slide 124, is mounted in the lower end wall 125 of the cabinet 20. Slidably connected to the coin slide 124 by means of a pin and slot connection 126—127, is a slide bar 128 (Figs. 14 and 16). Pivotedly connected to the slide bar 128, as at 129, is a member 130 which carries a laterally extending cam or pin 131. This pin 131 engages under an arm 132 which is pivotally mounted upon a horizontal rock shaft 133, the shaft 133 extending transversely across the cabinet 20 (Fig. 4); the member 130 being pivotally mounted at its lower end upon a horizontal rock shaft 134 which extends parallel to the rock shaft 133 below the latter (Figs. 4 and 16).

Mounted on the shaft 134 is an arm 136 (Fig. 13) and floating, that is, loosely mounted, on the shaft 134 is a segmental rack bar or gear 137 which has an arm 138, this arm 138 being provided with a lateral extension 139 in which is mounted a set screw 140. The segmental gear 137 meshes with a gear 141 which is rotatably mounted upon a shaft 142 that projects from a vertical supporting wall 143 which is arranged in the cabinet 20. The gear 142 in turn meshes with a gear 144 that is mounted on the shaft 72.

When the coin slide 124 is pushed inwardly, right to left (Fig. 16), the link mechanism 128—129—130 rocks the shaft 134 (counterclockwise, Fig. 13), thereby engaging the arm 136 with a screw 140 which is carried by the arm 138—139 of the segmental gear 137, thus causing the segmental gear 137 to be rotated (counterclockwise, Fig. 13). This movement of the gear 137 acts through the gears 141 and 144 to rotate the shaft 72 (counterclockwise, Figs. 10 and 13), thereby resetting the ratchet 71, and the arm or lug 77 which is carried by the shaft 72, and at the same time tensioning the operating spring 73 for the shaft 72.

The latch bar 61 is formed as a part of a rectangular frame or carriage which includes side members 145 and a horizontal bar 146 (Figs. 5 and 11). Mounted on the shaft 134 (Fig. 11) is an arm 147 which has a cam portion 148.

When the coin slide 124 is pushed inwardly (right to left, Fig. 16); and the shaft 134 rocked (counterclockwise, Fig. 11), through the action of the slide bar 128—129—130, the arm 147 on the shaft 134 is rocked (counterclockwise, Fig. 11), thereby causing the cam portion 148 of the arm 147 to engage the horizontal bar portion 146 of the rectangular latching member 61—145—146, thus rotating the member 61—145—146 (clockwise, Fig. 11). This motion of the member 61—145—146 disengages the latch bar 61 thereof from the main timing gears 56, whereupon the timing gears 56 being freed are rotated and reset, under the action of the tensioned operating spring 168, into their initial or zero position 150

(counterclockwise, Figs. 10 and 11), this resetting motion being imparted to the shaft 55 and timing gears 56 from the spring 168 by way of the elevator shaft 41, and gears 110 and 107 (Figs. 6 and 9).

During the above-mentioned movement of the shaft 134 and carriage 61—145—146 (counterclockwise, Fig. 11), the arm 147 is lifted from its position (Fig. 11) into dotted line position (Fig. 10) and in the latter position it engages a laterally extending pin or stop member 149 provided on one of the main timing gears 56 (Fig. 10) and thereby stops all of the main timing gears 56 in their reset or zero position.

Formed on one lateral side of the rotary elevator disc 36 is a cam 150 (Figs. 6, 7 and 8) which has an upwardly angled end portion 151. Mounted on the shaft 133 is a latch arm 152 which has an angled or laterally extending end portion 153 (Fig. 6) which is adapted to ride the surface of the cam 150 as the rotary elevator disc 36 is operated. However, when the rotary elevator disc 36 comes into position to elevate to the ramp 23 the last of a predetermined number of balls allowed the player for a coin inserted into the coin aperture of the coin slide 124, that is, for one of same, the angled end portion 153 of the latch arm 152 engages the angled end portion 151 of the cam 150 and thereby locks the elevator disc 36 against further rotation or operation (clockwise, Figs. 7 and 8) so that no more balls can be elevated to the ramp 23. However, when a proper coin is inserted into the coin aperture of the coin slide 124 and the latter and the slide bar 128 are pushed inwardly (right to left, Fig. 16), the cam 131 on the link 130 engages the arm 132 on the shaft 133 and thereby rotates the shaft 133 (counterclockwise, Figs. 7, 8, and 16). This movement of the shaft 133 lifts the latch arm 152 carried thereby up from the cam 150 and above the angled end portion 151 thereof, but at the same time engages the angled end portion 153 of the latch arm 152 with a laterally extending stop member 154 which is carried by the elevator disc 36 (Fig. 8). This engagement of the angled end portion 153 of the latch arm 152 with the stop 154 prevents the player from operating the elevator disc 34 while holding the coin slide 124 pressed inwardly, thus preventing fraudulent continuous operation of the game apparatus, or so-called "milking". However, when the coin slide 124 is released, the angled end portion 153 of the latch arm 152 drops (clockwise, Fig. 8) between the angled end portion 151 of the cam 150 and the stop 154 and thereby frees the elevator disc 36 for further operation.

Pivottally suspended from the vertical supporting wall 42 is a pendulum 155 (Fig. 9) and when the new game apparatus and its cabinet 20, are in proper playing position, the upper end portion of the pendulum 155 is latchingly engaged with a latch member 156; the latch member 156 being mounted upon a horizontal shaft 157 which extends transversely across the cabinet 20 below the inclined playing board 21.

Pivottally connected to the latch member 156, as at 158, (Fig. 9) is a slide bar 159 which is slidably mounted on the vertical supporting wall 42 by means of a pin and slot connection 160 (Figs. 6 and 9). This slide bar 159 has a lateral extension 161 (Fig. 6) which projects over the peripheral surface of a score-registering dial 162 that is loosely mounted upon, that is, floats upon, the elevator shaft 41 (Fig. 6); the registering dial 162 being integrally connected to the gear 110 by

means of a flanged sleeve 163 which is arranged upon the elevator shaft 41; this sleeve 163 having a flanged portion 169 (Figs. 6 and 17) which provides a housing for the main operating spring 168, the score-indicating or registering dial 162 being fastened to the housing portion 169 of the sleeve 163 so as to rotate therewith.

Carried by the shaft 157, adjacent the vertical supporting wall 143, is an arm 122 (Fig. 13) and pivottally connected at its lower end to this arm 122 is a member 119 which is loosely mounted upon, that is, floats upon, the shaft 58; the member 119 having a counterweighted portion 120, which is normally latched in raised, or full line, position (Fig. 13) by latching engagement of the upper end portion of the pendulum 155 with the latch member 156.

If the player attempts to operate the new game apparatus fraudulently by tilting the same and its cabinet 20 from their proper playing position, the upper end portion of the pendulum 155 is moved by gravity out of latching engagement with the latch member 156, whereupon the counterweighted end portion 120 of the member 119 drops or pivots by gravity (counterclockwise, Fig. 13) upon its supporting shaft 55, thereby elevating the member 119 into a position (as in dotted lines, Fig. 13) between the peripheral face of the printing drum 34 and the impression transmitting or pressure member 87, thus preventing the player from printing the score of his game upon the ticket web 30. At the same time this motion of the counter-weighted member 119—120 acts through the link 121 and the arm 122 to rotate the shaft 157 (clockwise, Fig. 13, counterclockwise, Fig. 9), thereby sliding the bar 159 (right to left, Fig. 9) and thus projecting the angled or lateral extension 161 of the slide bar 159 across the peripheral surface of the score-indicating dial 162, thereby rendering the player's total score invisible to him through the sight opening 165 which is provided in the cabinet 20 for the purpose of indicating to the player his total score at any stage of the game (Fig. 1).

To reset the anti-tilting device 155—156—157 and associated parts, that is, to retract the lateral extension 161 of the slide bar 159 out from under the sight opening 165, and to remove the member 119 from position between the printing drum 34 and the pressure member 87 (Fig. 13), it is necessary for the player to insert a proper coin into the coin aperture of the coin slide 124 and operate the various mechanisms hereinbefore described, including the segmental gear 137; and when the segmental gear 137 is moved from dotted to full line position, Fig. 13, its upper edge engages a laterally projecting pin 166 carried by the counterweighted portion 120 of the carriage 119 (Fig. 13), thereby pivoting the latter (clockwise Fig. 13). This movement of the counterweight 120 retracts the member 119 from dotted to full line position (Fig. 13), so that the impression transmitting or pressure member 87 may again force the web 30 against the printing drum 34, while at the same time this movement of the member 119—120 acts through the link 121 and arm 122 to rotate the shaft 157 (clockwise, Fig. 9), thereby moving the slide bar 159 from left to right, Fig. 9, and retracting the lateral extension 161 thereof out from under the sight opening 165, thus again exposing the score-indicating or register dial 162 to the player. At the same time this motion of the slide bar 159 (left to right, Fig. 9) reengages the latch member 156 with the upper end portion of the pendulum 155 so as to latch the counterweighted

end portion 120 of the member 119 in raised, full line, position, (Fig. 13).

Any suitable means (not shown) may be provided for inking the printing type 60 on the printing drum 34, the type 60 being preferably rubber type.

Operation

In order to play the new game apparatus, a player inserts a coin of proper denomination into

10 the coin aperture of the coin slide 124 and pushes the latter inwardly to discharge the coin into a suitable receptacle 176 provided therefor in the cabinet 20 whereupon the player may elevate the playing balls 167 one at a time up to the ramp

15 23 by depressing the elevator operating handle or lever 33 (from full to dotted line position, Fig. 3). This movement of the elevator operating handle or lever 33 is transmitted to the rotary elevator disc 36 by way of the link 46, pawl

20 44—48, ratchet 43, and elevator shaft 41 (Fig. 3), whereupon the rotary elevator disc 36 is rotated (counterclockwise, Fig. 3) and the balls 167 carried in the pockets 37 of the elevator disc 36 are discharged one at a time from their pockets 37

25 into the ramp 23 in front of the propelling device or plunger 24 by means of which they may be propelled by the player one at a time up the ramp 25 onto the upper portion of the inclined playing board 21 so that they may gravitate over the

30 inclined playing board 21 and, perchance, enter into one of the ball exit or scoring openings 22 through which they drop below the inclined playing board 21 into the corresponding inclined runways 25.

35 Each time the elevator operating handle 33 is depressed to operate the rotary elevator disc 36 and elevate a ball 167 up to the ramp 23, the elevator shaft 41 is rotated, step by step, (counterclockwise, Fig. 3), thereby tensioning, and storing 40 energy in the main operating coil spring 168; this being by reason of the fact that the innermost coil of the spring 168 is attached to a sleeve 170 that is fast upon the elevator shaft 41 while the outermost coil of the same is attached to the 45 flanged housing portion 169 of the sleeve 163.

A played ball traveling down one of the runways 25 passes into the corresponding vertical chute 26 (Figs. 10 and 12) and engages the portion 27 of the arm 28 of the corresponding timing gear carriage 57 thereby pivoting the thus actuated timing gear carriage 57 (counterclockwise, Fig. 12) on its supporting shaft 58 against the action of its counterweight 175. This motion of the actuated timing gear carriage 57 disengages 55 the latch member 61 from latching engagement with the main timing gears 56, thereby freeing the main timing gears 56, and their supporting shaft 55 and the printing drum 34 carried thereby, all of which are then rotated, (clockwise, Fig. 60 12, counterclockwise, Fig. 11), this motion of the shaft 55 and the timing gears 56 and printing drum 34 carried thereby being effected by the tensioned main operating spring 168, the energy 65 of the latter being transmitted by way of the sleeve 170, shaft 41, and gears 110 and 107 (Figs. 6 and 9).

The printing drum 34 being carried by the shaft 55 (Fig. 6) is, of course, rotated in unison with the timing gears 56 and shaft 55 to advance the printing type 60 on the drum 34 past and relative to the impression-receiving web 30. The duration of this rotation and the circumferential distance the printing drum 34 is rotated is determined as follows: As the ball-actuated timing gear carriage 57 is pivoted (counterclockwise,

Fig. 12) to release the latch member 61 from the main timing gears 56, so as to release the latter, shaft 55, and printing drum 34 for circumferential movement or rotation, the corresponding one of the auxiliary timing gears 59 is meshed with its main timing gear 56 (as in Fig. 12), and during this operation of meshing a pair of the timing gears 59—56, the laterally extending pin 67 carried by the actuated auxiliary timing gear 59 (Figs. 11, 12, 18 and 19) rides up the cam surface 66 of its timing gear lever 63; and as the shaft 55 and main timing gears 56 begin to rotate under the action of the main operating spring 168, the actuated auxiliary timing gear 59 is urged (clockwise, Fig. 18), by engagement with the corresponding main timing gear 56, thereby pivoting the corresponding timing lever 63 (counterclockwise, Fig. 18) into engagement with its stop 157, thus forcing the pin 67 off from the cam surface 66 of the timing lever 63 (right to left, Fig. 18), and at the same time pivoting the actuated timing gear carriage 57 (clockwise, Fig. 12), thus reengaging the latch bar 61 with the main timing gears 56 and thus stopping further rotation of the timing gears 56, shaft 55, and printing drum 100 34. The length of time required for the pin 67 to complete a cycle of operations and to ride up onto and off from the cam 66 thus determines the direction of rotation the corresponding timing gear 56, shaft 55, and printing drum 34, and the 105 length of time required for this cycle varies in the different sets of timing pins 67 and cams 66 so that the circumferential distance that the timing gears 56, shaft 55, and pivoting drum 34 are rotated varies in accordance with a predetermined relationship between the time required for a particular pin 67 to ride up onto and off from its corresponding cam 66 and the scoring value of the ball exit scoring opening 22 and runway 25 through which the played ball has passed 110 115 to actuate the corresponding timing gear carriages 27—28—55.

After a ball has thus engaged the portion 27 of one of the carriage arms 28 it passes from the corresponding chute 26 into the ball return runway 35 wherein it falls upon or engages the arm 69 of the pawl 70, thereby pivoting the pawl 70 (clockwise, Figs. 10 and 11) and thus circumferentially advancing the ratchet 71 and its supporting shaft 72 one step. This operation is repeated for each ball played and when the elevator operating handle 33 is depressed a predetermined number of times equal to the number of balls allowed the player for each game, the arm 75 of the pawl 70 engages the uninterrupted 120 smooth surface 74 of the ratchet 71, whereupon the ratchet 71, and its supporting shaft 72 are rotated a circumferential distance equal to the circumferential length of the uninterrupted surface 74 of the ratchet 71, (clockwise, Figs. 10 and 125 11) by the action of the tensioned spring 73 which is arranged upon the shaft 72 (Fig. 5). This rotation of the shaft 72 causes the arm 77 carried thereby (Fig. 15) to rotate (clockwise, Fig. 15) into engagement with the arm 78 of the latch member 79, whereupon the latch member 79 is pivoted (counterclockwise, Fig. 15) against the action of its resetting spring 171, thus moving its latching end portion 81 out of latching engagement with the notched portion 82 of the disc 83 130 that is arranged upon the shaft 84. At the same time, the depression of the elevator operating handle 33 acts through the elevator disc 34, shaft 41, sprocket 106, sprocket chain 105, and sprocket 104 to rotate the shaft 100 and disc 111 (clock- 135 140 145 150

wise, Fig. 15), thus causing one of the pins 112 on the disc 111 to engage the foot portion 113 of the stop member 113—114—115—117 and pivot the latter (clockwise, Fig. 15) out of engagement with the lateral extension 118 of the disc 83, whereupon the tensioned spring 68 which is arranged about the shaft 84 (Fig. 5), rotates the shaft 84 and its disc 83 (clockwise, Fig. 15), thereby moving the eccentric operating arm 85 (right to left, Fig. 15) and thus swinging the impression-transmitting or pressure member 87 and the flat spring 123 carried thereby (clockwise, Fig. 13, counterclockwise, Fig. 14) into engagement with the impression-receiving web 30; thereby forcing the web 30 against the score-recording printing type 60 carried by the printing drum 34 and recording thereon the total score of the game. During the score-printing operation the score-bearing or printed portion of the web 30 is sheared from the body of the same by the shearing action of one arm 89 of the pressure member 87 against the cutting edge 93 of the knife 135 (Fig. 14), thereby severing the score-bearing ticket portion of the web 30 from the body of the latter, whereupon the thus severed score-bearing ticket portion of the web falls by gravity upon the chute 94 and is dispensed exteriorly of the cabinet 20, through the outlet 31, to the player (Figs. 13 and 14).

The spring 68 on the shaft 84 is tensioned, and energy stored therein to operate the pressure member 87, and a step by step motion is imparted to the web-advancing roller 98, every time the player depresses the elevator operating handle or lever 33 to elevate a ball up into the ramp 23; this motion of the elevator-operating handle 33 being imparted to the shaft 84, to tension the spring 68, by way of the shaft 41, sprocket 106, sprocket chain 105, and sprocket 108 (Figs. 6 and 9), while at the same time this motion of the elevator-operating handle 33 is transmitted to the web-advancing roller as follows: When the elevator-operating handle 33 is depressed (Fig. 3) it rotates the elevator disc 36 and the elevator shaft 41 (counterclockwise, Fig. 3, clockwise, Fig. 9), and this motion of the elevator shaft 41 is transferred through the sprocket 106, sprocket chain 105 and sprocket 104 to the shaft 100, to rotate the latter (counterclockwise, Fig. 9). This rotation of the shaft 100 is transmitted through the beveled gears 101 and 102 to the vertical shaft 103 upon which the web-advancing roller 98 is mounted, thereby rotating the latter and thus advancing the web step by step through the slot 95 in the vertical supporting wall 92 across the cutting edge 93 of the knife 135 and across the peripheral surface of the printing drum 34 and the type 60 carried thereby so that the free end portion of the web 30 is thus always disposed in position to have the player's total score imprinted thereon at the end of the game by action of the pressure member 87, in the manner hereinbefore described.

When a coin of proper denomination is inserted into the coin-receiving aperture of the coin slide 124 and the latter is pushed inwardly into coin-discharging position (right to left, Fig. 16) the link mechanism 128—129—130 rocks the shaft 134 (counterclockwise, Figs. 13 and 16), thereby engaging the arm 136 which is carried by the shaft 134, with the screw 140 which is carried by the lateral extension 139 of the arm 138 of the segmental gear 137, thus causing the segmental gear 137 to be rotated (counterclockwise, Fig. 13). This movement of the segmental gear

137 acts through the gears 141 and 144 to rotate the ratchet-supporting shaft 72 (counterclockwise, Figs. 10 and 13), thereby resetting the ratchet 71 back into its initial position (as in Fig. 10) and at the same time tensioning the ratchet operating spring 73 so that the spring 73 will again rotate the shaft 72 and its arm 77 to release the latch member 79 from latching engagement with the cam 83 so that the pressure member 87 may again be urged by the tensioned spring 68 against the web 30 after a predetermined number of balls have been elevated to the propelling device 24 and the player's game completed.

The inward movement of the coin slide 124 into coin-discharging position, acts through the link mechanism 128—129—130 to rock the shaft 134 and its arm 147 cam 148 (counterclockwise, Fig. 11), thereby causing the cam 148 to engage the horizontal rod portion 146 of the latch member 61, thereby raising the said portion 146 and pivoting the latch bar 61, (clockwise, Fig. 11) out of latching engagement with the main timing gears 56, whereupon the main timing gears 56, being thus freed, are rotated or reset by the main operating spring 168, back into their initial or zero positions, wherein they are stopped and held, by latching engagement of a lateral extension 172 of the arm 147 with the pin or stop member 149 which projects from one of the main timing gears 56 (Fig. 5), until the coin slide 124 is retracted (by a resetting spring, not shown) back into coin-receiving position (left to right, Fig. 16), whereupon the link mechanism 128—129—130 associated with the coin slide 124 acts to rotate the shaft 134 (clockwise, Figs. 10 and 16), thus moving the lateral extension 171 of arm 147 out of engagement with the stop pin 149 so as to permit further rotation of the timing gears 56 when the latch bar 61 is again moved against the action of its resetting spring 173, (Fig. 10) out of latching engagement with the timing gears 56 by operation of the next timing gear carriage 57 to be operated by a ball passed down a runway 25.

The registering dial 162 is advanced in a circumferential step by step movement, in accordance with the score of the game, as follows: Every time one of the main timing gears 56 and their common supporting shaft 55 are ratched a predetermined circumferential distance by the operation of a played ball, in the manner hereinbefore described, this motion of the shaft 55 is transmitted through the gear 107 thereon to the gear 110 on the elevator shaft 41 which also carried the registering dial 162 (Fig. 6), the registering dial 162 "floating", that is, being loosely mounted on, the elevator shaft 41 and being fastened to the flanged portion 169 of the sleeve 163 that is arranged upon the elevator shaft 41 (Figs. 6 and 17).

If the player attempts to operate the new game apparatus fraudulently by tilting the same and its cabinet 20 from their proper playing position, the upper end portion of the pendulum 155 is moved by gravity out of latching engagement with the latch member 156, whereupon the counterweighted end portion 120 of the member 119 drops or pivots by gravity (counterclockwise, Fig. 13) upon its supporting shaft 55, thereby elevating the member 119 into a position (as in dotted lines, Fig. 13) between the peripheral face of the printing drum 34 and the impression transmitting or pressure member 87, thus preventing the player from printing the score of 150.

his game upon the ticket web 30. At the same time this motion of the counterweighted member 119—120 acts through the link 121 and arm 122 to rotate the shaft 157 (counterclockwise, Fig. 9, 5 clockwise, Fig. 13), thereby sliding the bar 159 (right to left, Fig. 9) and thus projecting the angled or lateral extension 161 of the slide bar 159 across the peripheral surface of the score-indicating dial 162, thereby rendering the player's 10 total score invisible to him through the sight opening 165 which is provided in the cabinet 20 for the purpose of indicating to the player his total score at any stage of the game (Fig. 1).

To reset the anti-tilting device 155—156—157 15 and associated parts, that is, to retract the lateral extension 161 of the slide bar 159 out from under the sight opening 165, and to remove the member 119 from position between the printing drum 34 and the pressure member 87 (Fig. 13), 20 it is necessary for the player to insert a proper coin into the coin aperture of the coin slide 124 and operate the various mechanisms hereinbefore described, including the segmental gear 137; and when the segmental gear 137 is moved from 25 dotted to full line position, Fig. 13, its upper edge engages a laterally projecting pin 166 carried by the counterweighted portion 120 of the carriage 119 (Fig. 13), thereby pivoting the latter (clockwise Fig. 13). This movement of the counterweight 120 retracts the member 119 from dotted to full line position (Fig. 13), so that the impression transmitting or pressure member 87 may again force the web 30 against the printing drum 34, while at the same time this movement of the 30 member 119—120 acts through the link 121 and arm 122 to rotate the shaft 157 (clockwise, Fig. 9, 35 counterclockwise, Fig. 13), thereby moving the slide bar 159 from left to right, Fig. 9, and retracting the lateral extension 161 thereof out 40 from under the sight opening 165, thus again exposing the score-indicating or register dial 162 to the player. At the same time this motion of the slide bar 159 (left to right, Fig. 9) reengages the latch member 156 with the upper end portion 45 of the pendulum 155 so as to latch the counterweighted end portion 120 of the member 119 in raised, full line, position, (Fig. 13).

While we have illustrated and described the preferred form of construction for carrying our 50 invention into effect, this is capable of variation and modification, without departing from the spirit of the invention. We, therefore, do not wish to be limited to the precise details of construction set forth, but desire to avail ourselves of 55 such variations and modifications as come within the scope of the appended claims.

Having thus described our invention what we claim as new and desire to protect by Letters Patent is:

60 1. In a game apparatus, the combination of: a cabinet having a dispensing outlet and including a member providing a playing surface and said member having ball exit scoring openings therein; an inscription-receiving web in said cabinet; means including members automatically actuated by balls passing through said ball exit scoring openings to record the score of the game upon a portion of said web after a predetermined number of balls have been played; and automatic means coacting with said recording means 65 both to sever the said portion of said web from the body of the latter and to dispense the said portion of said web thus severed from the body of the same through said dispensing outlet to 70 the player.

2. In a game apparatus, the combination of: a cabinet having a dispensing outlet and including an inclined playing board provided with ball exit scoring openings; means for elevating balls one at a time up to the level of said inclined playing board; means for propelling balls one at a time onto the upper portion of said inclined playing board so that they may gravitate thereover and enter into said ball exit scoring openings; inclined runways below said playing board and having communication with said scoring openings for returning balls from said scoring openings to said elevating means; an inscription-receiving member in said cabinet; means including members actuated by balls traveling along said runways to record the score of the game upon said inscription-receiving member after a predetermined number of balls have been elevated to said playing board; and means coacting with said elevating means and recording means after a predetermined number of balls have been elevated to said playing board to dispense said inscription-receiving member to the player through said dispensing outlet.

3. In a game apparatus, the combination of: a cabinet provided with a dispensing outlet and including a member providing a playing surface and said member having ball exit scoring openings therein; means for propelling balls one at a time over said playing surface so that they may enter into said scoring openings; means for elevating spent balls one at a time up to said playing surface; runways below said playing surface and having communication with said ball exit scoring openings for returning the played balls from said scoring openings to said elevating means; an inscription-receiving web in said cabinet; means including members actuated by balls traveling along said runways to record the score of the game upon a portion of said web after a predetermined number of balls have been elevated to said playing surface; and means coacting with said elevating means after a predetermined number of balls have been elevated thereby to sever the said portion of said web from the body of the latter and to dispense the said portion of said web to the player through said dispensing outlet.

4. In a game apparatus the combination of: a cabinet including a member providing a ball playing surface; means for propelling balls one at a time over said playing surface; means for elevating spent balls one at a time up to said playing surface; means for returning the played balls from said playing surface to said elevating means; an inscription-receiving web in said cabinet; means including members actuated by balls traveling from said playing surface to said elevating means by way of said ball returning means to record the score of the game upon a portion of said web after a predetermined number of balls have been elevated to said playing surface; and means coacting with said elevating means after a predetermined number of balls have been elevated thereby to sever the said portion of said web from the body of the latter and to dispense the said portion of said web to the player through said dispensing outlet.

5. In a game apparatus, the combination of: a cabinet having a dispensing outlet and including a member providing a playing surface; means for propelling balls one at a time over said playing surface; means for elevating balls one at a time from a point below said playing surface up to said propelling means; means

- for returning the played balls from said playing surface to said elevating means; an inscription-receiving member in said cabinet; means including members actuated by balls traveling from said playing surface to said elevating means by way of said ball-returning means to record the score of the game upon said inscription-receiving member after a predetermined number of balls have been elevated to said playing surface; and means coacting with said elevating means after a predetermined number of balls have been elevated thereby to dispense said inscription-receiving member to the player through said dispensing outlet. 10
- 5 6. In a game apparatus, the combination of: a cabinet including a member providing a playing surface; means for propelling balls over said playing surface; an inscription-receiving web in said cabinet; means including members actuated by the played balls to record the score of the game upon a portion of said web after a predetermined number of balls have been played; and means automatically severing the said portion of said web from the body of the same after the score recording operation and after the said predetermined number of balls have been played. 25
7. In a game apparatus, the combination of: a cabinet having a dispensing outlet and including an inclined playing board having ball exit scoring openings formed therein; means for propelling balls one at a time onto the upper portion of said playing board so that they may gravitate thereover and enter into said scoring openings; means including a manually operable member for elevating balls one at a time from a point below said scoring openings to said propelling means; an imprint-receiving web in said cabinet; inclined ball return runways below and in communication with scoring openings for returning the played balls from said scoring openings to said elevating means; a printing drum in said cabinet; means including members operated by balls traveling down said runways to rotate said printing drum in a step by step movement in known accordance with the scoring value of said balls and scoring openings; means coacting with said manually operable member for advancing said web relative to and past said printing drum; means coacting with said manually operable member to urge said web into printing engagement with said printing drum, after a predetermined number of balls have been elevated to said playing board by said elevating means; and means for severing the printed score-bearing portion of said web from the body of the same after said printing operation and for dispensing the same to the player through said dispensing outlet. 40
- 55 8. In a game apparatus, the combination of: a cabinet having a dispensing outlet and including a member providing a ball playing surface and said member having scoring openings therein; means for projecting balls one at a time over said playing surface so that they may enter into and pass through said scoring openings; means for elevating spent balls one at a time from a point below said playing surface and scoring openings up to said propelling means; runways below said playing surface for returning the played balls from said scoring openings to said propelling means; an imprint-receiving member in said cabinet; printing means in said cabinet; means actuated by balls traveling along said runways for advancing said printing means in a step by step movement in known accordance 75
- with the scoring value of said balls; and means coacting with said elevating means after a predetermined number of balls have been elevated thereby to said playing surface to engage said printing means and imprint-receiving member with each other so as to print the total score of the game upon the latter and dispense the same thus printed to the player exteriorly of said cabinet by way of said dispensing outlet. 20
9. In a game apparatus, the combination of: a cabinet including a member providing a playing surface and said member having ball exit scoring openings therein; means for propelling balls one at a time over said playing surface so that they may enter into and pass through said scoring openings; means for elevating spent balls one at a time from a point below said playing surface and scoring openings up to said playing surface; printing means in said cabinet; an impression-receiving member in said cabinet; means coacting with said elevating means for urging said printing means and impression-receiving member into printing engagement with each other after a predetermined number of balls have been elevated by said elevating means up to said playing surface so as to imprint upon said impression-receiving member the total score of the game and to dispense the said impression-receiving member thus printed to the player exteriorly of said cabinet. 25
- 10 10. In a game apparatus, the combination of: a cabinet including a member providing a ball playing surface; means for propelling balls one at a time over said playing surface; means for elevating spent balls one at a time from a point below said playing surface up to said propelling means; means for returning played balls from said playing surface to said elevating means; printing means in said cabinet; imprint-receiving means in said cabinet; means operated by the played balls passing along said ball-returning means for advancing the said printing means past the said imprint-receiving means in a step by step movement in known accordance with the scoring value of the played balls; and means coacting with said elevating means after a predetermined number of balls have been elevated thereby up to said playing surface to urge said printing means and imprint-receiving means into printing engagement with each other so as to print the total score of the game upon the latter and dispense the same thus printed exteriorly of the cabinet to the player. 110
11. In a game apparatus, the combination of: a cabinet including an inclined playing board having ball exit scoring openings formed therein; means for propelling balls one at a time onto said playing board so that they may enter into and pass through said scoring openings; means for elevating balls one at a time from a point below said playing board up to the level of the same; inclined runways below said playing board each having communication with a preselected group of said scoring openings; a common runway for returning the played balls from said inclined runways to said elevating means; a score printing device in said cabinet; means including devices arranged in said inclined runways and operable by balls traveling therealong to total the score of the game upon said printing device; and means coacting with said printing device and elevating means to print the score of the game after a predetermined number of balls have been elevated by said elevating means up to the level of said playing board. 130

12. In a game apparatus, the combination of:
 a cabinet including an inclined playing board
 having ball exit scoring openings formed there-
 in; means for projecting balls one at a time onto
 5 the upper portion of said playing board so that
 they may gravitate thereover and enter into and
 pass through said scoring openings to a point
 below said playing board; means for elevating
 the played balls one at a time from a point be-
 10 low said playing board up to the level of the
 same; runways for conducting the played balls

from said scoring openings to said elevating
 means; and means including a device operable
 by balls passing along said runways from said
 scoring openings to said elevating means and co-
 acting with the latter to print the total score
 80 of the game after a predetermined number of
 balls have been elevated by said elevating means
 up to the level of said playing board.
